UNITED STATES PATENT OFFICE.

WILLIAM G. ACKERMAN, OF WESTPOINT, NEBRASKA.

SHARPENER FOR HAIR-CLIPPERS

1,141,095.

Specification of Letters Patent. Patented June 1, 1915.

Application filed January 12, 1915. Serial No. 1,825.

To all whom it may concern.

Be it known that I, WILLIAM G. ACKERMAN, a citizen of the United States, residing at Westpoint, in the county of Cuming and 5 State of Nebraska, have invented certain new and useful Improvements in Sharpeners for Hair-Clippers; and I do hereby declare the following to be a full, clear, and exact description of the invention, such as will 10 enable others skilled in the art to which it appertains to make and use the same.

This invention relates to a device for sharpening the blades used in hair clippers, and the primary object of the invention is 15 to provide a sharpening device which will efficiently sharpen the blades used in a hair clip by the application of a whetting or sharpening stone to the surface of the blades which engage each other, for evenly sharpening the entire surfaces of the blades for 20 insuring the efficient cutting operation thereof.

Another object of this invention is to provide a sharpener as specified which embodies 25 a reciprocably movable sharpening stone, means for reciprocating the stone and for holding the clipper blade firmly upon the upper surface of the sharpening stone during the reciprocatory movement of the stone 30 for efficiently sharpening the blade.

With the foregoing and other objects in view this invention consists in such novel features of construction, combination and arrangement of parts as will be hereinafter 35 more fully described, illustrated in the accompanying drawings and claimed.

In describing the invention in detail reference will be had to the accompanying drawings wherein like characters designate 40 like or corresponding parts throughout the several views, and in which—

Figure 1 is a side elevation of the improved sharpener, Fig. 2 is a top plan view of the sharpener showing parts thereof 45 broken away, Fig. 3 is a vertical cross sectional view through the sharpener, Fig. 4 is a fragmentary top plan view of the sharpener, Fig. 5 is a fragmentary vertical sectional view through the sharpener, and Fig. 50 6 is a detail bottom perspective view of the clipper blade holding plate.

Referring more particularly to the drawings, 1 designates the supporting base of the sharpener, which has a vertical board 2 secured to the upper surface at one end thereof, which board rotatably carries shafts 3

and 4. The shaft 3 has a hand wheel 5 mounted thereupon, and also a gear 6 which gear is rotated by the manual rotation of the hand wheel 5. The gear 6 meshes with a pinion 7 carried by the shaft 4, for rotating the shaft 4 by the rotation of the hand wheel and the shaft 3. The shaft 4 has a disk 8 mounted thereupon, to which disk is eccentrically connected a pitman rod 9. The pitman rod 9 extends longitudinally along the upper surface of the supporting base 1, being spaced upwardly therefrom, and has its rear end connected to a slideable block 10. The block 10 is slideably mounted upon the plates 11 and 12, which plates are carried by suitable supporting legs 13'. The legs 13' are, in any way desired, connected to the supporting base 1 and extend upwardly therefrom, as is clearly shown in Fig. 1 of 75 the drawing. The plates 11 and 12 have their facing inner edges spaced from each other for forming a guideway in which is seated the lug 13. The lug 13 is formed upon and depends from the under surface 80 of the slideable block 10, and it guides the reciprocatory movement of the block, preventing the same from moving laterally during its longitudinal reciprocatory movement. The block 10 also has a bolt 14 inserted 85 therethrough, which extends through the opening 15 formed by the spacing of the inner side edges of the plates 11 and 12. The bolt 14 has a plate 15 secured to its under surface and held in slideable abutting engagement with the under surfaces of the plates 11 and 12 by a nut 16 which is mounted upon the end of the bolt. The plate 15 is provided for preventing vertical displacement of the slideable block 10 during the 90 movement thereof.

The block 10 is provided with longitudinally extending cut out portions 18 and 19, which receive the lower edges of upstanding plates 20 and 21. The plates 20 and 21 are 100 connected by bolts 22, which extend transversely across the upper surface of the block 10 and clamp the inner surfaces of the plates 20 and 21 into engagement with the sides of a sharpening stone 23, for holding the stone 105 attached to the block 10 for slideable movement therewith.

The supporting structure or base 1 has a standard 24 secured thereto, which standard has an arm 25 pivotally connected to its upper end. The arm 25 has its outer end reduced and provided with a plurality of 110

notches 26, for receiving a ring 27 which is carried by a weight 28. The arm 25 has positioned therebeneath, a clipper blade engaging plate 29, which plate is provided with a slot 30 formed in the upper face thereof, for receiving the lower edge of the arm or lever 25, as is clearly shown in Fig. 3 of the drawing. The plate 29 has outstanding pins 31 formed thereupon, which are provided for seating in the openings which are formed in a clipper blade shown at 32 in the drawings. The openings formed in the clipper blade in which the pins 31 are seated are the ordinary type of openings which are used for connecting the blade to the clipper supporting and operating construction.

In the operation of the improved sharpener heretofore described; the clipper blade 20 to be sharpened, is placed upon the plate 29, after which the lever or arm 25 is moved so that it will assume a horizontal position, and cause the under surface of the blade, which is to be sharpened to rest upon the upper surface of the sharpening stone 23. The weight 28 which is hung upon the outer end of the arm 25 will tend to force the blade against the upper surface of the stone for insuring the sharpening of the same upon the reciprocatory movement of the stone. The stone 25 is reciprocated, by the rotation of the hand wheel 5 which will rotate the shaft 4 through the meshing engagement of the gear 6 and the pinion 7. The rotation of the shaft 4, will owing to the eccentric connection between the piston rod 9 and the disk 8 reciprocate the supporting block 10 and the whetting or sharpening stone 23, for sharpening the blade 32 of the clipper.

40 From the foregoing description taken in connection with the accompanying drawings the advantages of construction and of the method of operation of the improved sharpener for hair clippers will be readily apparent to those skilled in the art to which this invention appertains and, while in the foregoing description, the principle of the operation of this invention has been described together with various features of 45 construction, it is to be understood that certain minor features of construction, combination and arrangement of parts may be altered to suit practical conditions provided such alterations are comprehended within 50 the scope of what is claimed.

What is claimed is:—

1. In a device for sharpening clipper blades, a supporting structure, a pair of horizontally disposed plates carried by said 60 supporting structure and having their facing sides spaced from each other, a block slidably mounted upon said plates, means for preventing vertical and lateral move-

ment of said block, a sharpening stone detachably carried by said block, and means 65 for holding a clipper blade in engagement with the upper surface of said sharpening stone, and means for moving said sharpening stone forwardly and rearwardly upon said supporting structure for sharpening 70 said blade.

2. In a device for sharpening clipper blades, a supporting structure, a pair of plates supported by said supporting structure and upwardly therefrom, in a horizontal plane, said plates having their facing sides spaced from each other, a block slidably mounted upon said plates, a depending lug formed upon said block and between the facing sides of said plates for preventing the 80 lateral movement thereof, means for preventing vertical movement of said slot, a sharpening stone detachably carried by said slot, a standard secured to said supporting structure, an arm pivotally connected to said standard, a plate having a clipper blade detachably attached thereto, said plate having a longitudinal groove formed in the upper face thereof for receiving the lower edge of said arm for holding said clipper blade in 90 engagement with the upper surface of said sharpening stone, and means for moving said sharpening stone forwardly and rearwardly upon said plate for sharpening said cutter 95 blade.

3. In a device for sharpening clipper blades, a supporting structure, a pair of horizontally disposed plates supported by said supporting structure and upwardly therefrom, said plates having their facing 100 sides spaced from each other, a block slidably mounted upon said plates, a pair of upstanding plates carried by said block and provided for gripping the side edges of the sharpening stone, means for tightening the grip of said plates upon the sharpening stone, a standard carried by said supporting structure, an arm pivotally carried by said standard, a plate for detachably supporting a clipper blade, said plate being provided with a longitudinal groove for receiving the lower edge of said arm for holding said clipper blade upon the upper surface of said sharpening stone, a pitman rod connected to said block and means for reciprocating said 110 pitman rod for moving said block longitudinally upon said plate for sharpening the under surface of said stone, and means for preventing vertical and lateral movement of said block and said stone.

In testimony whereof I affix my signature in presence of two witnesses.

WILLIAM G. ACKERMAN.
